UNITED STATES PATENT OFFICE.

ARCHIA L. ROSS, OF NEW YORK, N. Y.

DESIGN FOR A SKIRT-HANGER.

SPECIFICATION forming part of Design No. 33,069, dated August 14, 1900.

Application filed July 12, 1900. Serial No. 23,422. Term of patent 14 years.

To all whom it may concern:

Be it known that I, ARCHIA L. ROSS, a citizen of the United States, and a resident of the city of New York, borough of Manhattan, in the county and State of New York, have invented and produced a new and original Design for a Skirt-Hanger, of which the following is a full, clear, and exact description.

Reference is to be had to the accompanying drawing, forming a part of this specification, in which the figure is a perspective view of a skirt-hanger, showing my design.

The leading feature of the design consists in the configuration of the skirt-hanger made 15 the subject of the accompanying illustration.

The design in its entirety consists of a rectangular wire frame A, the lower side B ap-

pearing with spaced integral and transversely-extending hooks C and the upper side D appearing with integral horizontally-disposed eyes E and the interlocked ends F.

Having thus described my invention, I claim as new and desire to secure by Letters Patent—

The design for a skirt-hanger, as herein 25 shown and described.

In testimony whereof I have signed my name to this specification in the presence of two subscribing witnesses.

ARCHIA L. ROSS.
